UNITED STATES PATENT OFFICE.

SARAH J. COBEAN, OF ROYAL OAK, MICHIGAN.

DETACHABLE CLAMP OR NAME-PLATE.

SPECIFICATION forming part of Letters Patent No. 655,197, dated August 7, 1900.

Application filed December 26, 1899. Serial No. 741,609. (No model.)

To all whom it may concern:

Be it known that I, SARAH J. COBEAN, a citizen of the United States, residing at Royal Oak, in the county of Oakland, State of Michigan, have invented a certain new and useful Improvement in Detachable Clamps or Name-Plates for Belts or Animal-Collars; and I declare the following to be a full, clear, and exact description of the same, such as will enable others skilled in the art to which it pertains to make and use the same, reference being had to the accompanying drawings, which form a part of this specification, and to the letters of reference marked thereon, in which—

15 Figure 1 is a perspective view showing part of collar with clamp and name-plate attached. Fig. 2 is a front view of clamp, showing opening for name-plate. Fig. 3 is a back view of clamp, showing edges of clamp turned to engage with the belt or collar. Fig. 4 is a sectional view taken on line 4 4 of Fig. 1, showing name-plate, collar, and clamp. Fig. 5 is a sectional view of the name-plate, collar, and clamp combined on line 5 5 of Fig. 1.

25 My present invention relates to a detachable clamp for holding name-plates or license-tags; and it consists of a metal sheet so formed by having its edges turned as to be readily attached to or detached from a belt or animal-collar and having an opening through which the plate or card bearing the owner's name and address or the license-number and name of the animal may be easily read.

Similar reference-letters refer to like parts throughout the several figures.

In the accompanying drawings, A is a belt or collar.

B is a metal clamp, and C a name-plate or license-tag.

40 *a a* show that part of B that is turned so as to form a recess, into which the name-plate and belt or collar are inserted, which holds

the metal plate securely to the collar when the ends of the collar are fastened together. *b b* show end of clamp turned slightly, so as to 45 press firmly on the belt or collar, thus preventing the name-plate from working out. The clamp must be of metal sufficiently pliable to permit of turning its edges, so as to form a groove or recess for engaging the edges 50 of the belt or animal-collar.

Having thus fully described my invention, what I claim as new, and desire to secure by Letters Patent, is—

1. A detachable clamp or name-plate for 55 belts, collars and the like, consisting of a sheet of metal having its upper and lower edges turned over backward so as to overlap respectively the upper and lower edges of said belt or collar, and having its side edges turned 60 inward slightly so as to press firmly on said belt or collar, said sheet of metal also being provided with a slot or opening in its center and adapted to have a card inserted between said sheet and belt or collar so as to be visible through said slot, said card being securely retained in place by the inward turning of said side edges, substantially as set forth.

2. A detachable clamp or name-plate for 70 belts, collars and the like, consisting of a sheet of metal having its upper and lower edges turned over backward so as to overlap respectively the upper and lower edges of said belt or collar, and having its side edges turned inward slightly so as to press firmly on said 75 belt or collar, preventing said clamp from accidentally slipping, substantially as set forth.

In testimony that I claim the above as my invention I have hereunto subscribed my name in the presence of two witnesses.

SARAH J. COBEAN.
